UNITED STATES PATENT OFFICE.

JOHN A. WINTROATH, OF LOS ANGELES, CALIFORNIA, ASSIGNOR TO THE LAYNE & BOWLER CORPORATION, OF LOS ANGELES, CALIFORNIA, A CORPORATION OF CALIFORNIA.

BEARING SYSTEM FOR ROTARY WELL-PUMPS.

1,079,682.

Specification of Letters Patent.

Patented Nov. 25, 1913.

Application filed February 11, 1913. Serial No. 747,780.

To all whom it may concern:

Be it known that I, JOHN A. WINTROATH, a citizen of the United States, residing at Los Angeles, in the county of Los Angeles and State of California, have invented a new and useful Bearing System for Rotary Well-Pumps, of which the following is a specification.

This invention relates broadly to a novel bearing system for vertical rotary multi-stage pumps installed in wells; and more particularly this invention relates to a novelly constructed bearing having a novel location beneath the lowermost pump impeller, where-
10 by the excessive and damaging wear on the supplementary stage bearings between the impellers is altogether eliminated; and whereby the rapid depreciation and unreliability characteristic of prior well pumps
20 of this type may be avoided, so that the unsatisfactory multi-stage well pump hitherto known is converted into a durable, efficient and reliable adjunct to well mechanism. The provision of a bearing in the inlet passage
25 below the lowermost impeller has never been countenanced, because it was believed that a bearing so located would unjustifiably interfere with the hydraulic flow through said inlet passage. But by careful experiment I
30 have discovered that a bearing there located bears a peculiar hydraulic relation to the supplementary bearings above, whereby the influence of the former sheds a remarkably prominent and beneficial influence over the
35 latter so as to protect them against the damaging wear previously encountered.

Broadly, therefore, this invention rests on the discovery that a bearing, located beneath the lowermost impeller of a multi-stage well
40 pump, secures the unexpected advantages hereinafter disclosed; and furthermore, by the novel bearing construction hereinafter shown, these advantages may be secured without materially interfering with the hy-
45 draulic flow through the inlet pump passage.

The accompanying drawings illustrate the invention.

Figure 1 is a fragmental axial section through a well casing including a multi-stage well pump provided with my bearing system. Fig. 2 is a partial axial section through a novel bearing embraced in my invention. Fig. 3 is a plan view of the bearing shown in Fig. 2.

55 The well casing 1 is usually sunk deep

down to the water or oil bearing gravels, and a vertical rotary multi-stage pump 2 is usually suspended in said well casing and is positioned often several hundred feet beneath the surface of the earth. Pumps of 60 this construction have their inlet below, and the water or other fluid derived from said well is sucked into the pump through an inlet passage, including section pipe 3, bottom bearing 4 and the lower portion 5 of the 65 lowermost pump casing; and after passing through pump 2 said fluid is forced upward, against high head, through the riser 6 to the surface of the earth.

The pump 2 comprises a series of separate 70 and similar pump casings 7 mounted one above the other, each of said casings containing a pumping chamber or stage 8; and by means of cap screws 9 the lower periphery of one casing is securely attached to the 75 upper periphery of the next, until a sufficient number of casings have been thus connected to provide the requisite stages—five being shown in the drawings. The sides and bottom of each pumping chamber 8 is bounded 80 by the bowl portion 10 of the adjacent casing 7, while the top of said chamber is bounded by the plate 11 supported by curved diffusion vanes 12 which extend down from the bottom portion 13 of the casing next 85 above. Casing 7, diffusion vanes 12 and plate 11 are integrally cast, and between the diffusion vanes lie the usual fluid passages which connect two successive stages or pumping chambers 8, while the plate 11 is 90 flared upwardly into a central neck 14 so as to form a supplementary shaft bearing 15 between successive stages. The plate 11 of the uppermost pump casing is specially constructed and carries a long bearing neck 16, 95 usually having bronze bearing bushings 17; while the lowermost pump casing is rigidly connected with a separate bulged bearing casing 18 supporting bearing 19.

The power shaft 20 extends downward 100 from the surface of the earth to and through the casing constituting pump 2, said shaft being supported laterally within said pump by the bearing bushing 17, supplementary bearings 14 and bearing 19. A series of rotary impellers 21 are carried by shaft 20 and are operated in the pumping chamber 8 in the usual manner.

In prior multi-stage well pumps of the foregoing type there has been no shaft bear- 110

ing 19 located in the inlet pump passage or anywhere else beneath the lowermost impeller. The presence of a bearing there has always been discountenanced because of its interference with the hydraulic upward flow in said inlet passage, and in view of its peculiar influence on and coöperation with supplementary bearings 14 as hereinbefore described this invention basically consists in 10 providing a bottom bearing 19. This bottom bearing may have any suitable form, and a preferred construction is detailed in Figs. 2 and 3 and will now be described.

The casing 18 is bulged as at 22 in order 15 to house the similarly-formed bearing 19 and to afford fluid passage of equal cross area throughout the length of said bearing casing. For the purpose of parting the rising fluid without shock or friction, and for the purpose 20 of preventing the rising fluid from entering the bearing from below, the bearing 19 is completely closed around the shaft at its lower extremity, and this lower closing portion terminates in a point 24. The supporting webs, which unite casing 18 with bearing 19, have similarly-tapered lower edges 26, which also part the rising fluid without shock or friction.

The member 23 of bearing 19 is seen to 30 embrace the lower shaft extremity 27 and to carry a bronze bushing 28, which sustains the wear of said shaft, and which extends somewhat above the bearing member 23. The said member is formed with a seat 29 and a threaded neck 30, and onto this neck is screwed the up-standing bell-shaped cap 31 constituting a portion of bearing 19. The upper part of this cap fits nicely around shaft 20 as at 32, and the body of said cap 40 forms a chamber 33 surrounding or embracing said shaft above its lower extremity. Within said chamber is located a depending cap 34 rotatively supported on shaft 20 by set screw 35, and having an accurately machined central aperture 36 adapted to snugly embrace the shaft so as to form a water tight fit with the same. Caps 31 and 34, together with a suitable filtering and packing material 37 provided beneath cap 50 34, comprises a filtering attachment for bearing 19 and serves to protect said bearing as will be hereinafter described. A second depending cap 38 is rotatively bound on shaft 20 by set screw 39 and has an accurately machined central aperture 40 snugly embracing the shaft so as to form a water tight fit with the same; and for a purpose hereinafter disclosed, the said member laps over the upstanding cap or chamber 55 60 forming portion 31 of the bearing. It is noticed, however, that the outer face of said member practically forms a smooth continuous outer surface with bearing member 23 and cap 31, so that the upward hydraulic flow 65 encounters no resisting projections.

The peculiar protective influence which a bottom bearing 19, located beneath the lowermost impeller, sheds upon the supplementary bearings 15, and the hydraulic relations upon which this influence depends, 70 will now be described.

Ordinarily the lowermost stage or casing 7 of the pump is located beneath the surface of the earth at a point within reasonable proximity to the normal fluid level. This is often down several hundred feet, and when the fluid is being forced upward through the riser 6, each pump stage supports its proportionate share of the fluid head. For instance, if the five-stage pump, shown in 80 Fig. 1, were forcing the fluid upward against a 500-foot head the pressure increment of each stage would equal a head of 100 hydraulic feet. It will be noticed, however, that the mean hydraulic pressure in 85 the uppermost stage or casing 7 would be equal to the total 500-foot head above, while the mean pressure in the next lower stage would be only 400 feet, and in the next 90 lower stage 300 feet, and so on, until the 95 mean pressure in the lowest stage would only equal the 100 foot, which represents its own share of the total head supported by the pump. In other words, the mean pressure in each stage equals its own share of 100 the total head plus the head or pressure increments of all the stages below. With this in mind it will be seen that the lowermost of the series of supplementary bearings 15 is open to a great hydraulic head, both on 105 its upper and lower end, and that the successively higher supplementary bearings are subject to a similar but proportionately increased head, which becomes very severe in the uppermost supplementary bearing. In 110 wells of ordinary construction there is often considerable sand pumped along with the fluid, and as this enter the supplementary bearings 15 the same are rapidly worn large and therefore robbed of their bearing utility. 115 In the absence of a bottom bearing 19 the destructive grinding of the supplementary bearing is so prominent that vertical multi-stage well pumps have never been thoroughly satisfactory. Even though supplementary 120 bearings may have been accurately machined so as to embrace the shaft snugly, the aforesaid severe hydraulic pressures within the pump always forced the water through these supplementary bearings. After the same has been slightly worn the shaft tends to vibrate, and as the same pounds back and forth it drives the water and sand out of one side of the bearings, while the severe hydraulic pressure drives 125 the water and sand back into the other side of the bearings and the fluid pressure is so great that this water and sand circulation occurs, no matter how fine the crevices between the shaft and the bearings may be. 130

Were it not for the hydraulic pressure in the vicinity of the supplementary bearings, the water and sand might be driven from them and permanently excluded by the 5 slight normal movements of the shaft, but under the conditions of actual service such exclusion is obviously impossible. In prior pumps, where a bottom bearing was not provided, the supplementary bearings soon became sand-worn in the aforesaid manner and permitted an increasingly aggravated vibration of the shaft until the pump literally rattled itself to destruction. All this, however, is avoided by using a bottom bearing 10 as set forth in this specification and located beneath the lowermost impeller where the hydraulic pressure is altogether negligible, so that said bearing, in view of its position, is practically immune from sand 15 and water circulation.

The fluid pressure is zero at the surface level of any standing fluid, and, since the lowermost stage of the pump is usually located reasonably near the fluid level in 20 the well, it is obvious that the hydraulic pressure adjacent bearing 19 will be virtually zero. In this event there is no hydraulic component tending to drive a film of water and sand between the bottom bearing 25 and the shaft extremity which it embraces. The bottom bearing is machined so as to fit and embrace the shaft nicely, and in the absence of a great hydraulic head the circulation of water and sand in said bearing 30 is practically eliminated. Furthermore, in addition to the low pressure, the fluid flows upward around the bottom bearing, and the same being completely closed below, no water or sand will enter it except by an unlikely and unnatural counter or down flow 35 leading through the descending annular passage between caps 31 and 34. The little sand and fluid, however, that may find this course must pass through the packing or 40 filtering material 37 where all sand and other grit is extracted from the fluid which may then safely enter any crevice between bushing 28 and shaft 20. This clean water 45 is no detriment to the bearing, but actually exerts a beneficial lubricating action between the bearing parts. Cap 38 is provided 50 so that the water, which descends from the riser and pump, after the latter is shut down, will be deflected outward and away 55 from the aperture between cap 31 and shaft 20.

In practice it is found that a bottom bearing located in the substantially pressureless zone beneath the lowermost impeller, has a 60 remarkably good wearing capacity, while the supplementary bearings 15, located in the high pressure zones aforesaid, have a noticeably poor and inefficient wearing capacity. This condition, as has been explained, is 65 chiefly due to the relative locations of said

bearings with respect to local hydraulic pressures, but is also aided by the manner in which the bottom bearing may embrace and seal the lower extremity of the shaft so as to prevent circulation, while the supplementary bearings, being necessarily open above and below, are subject to a constant fluid and sand flow through and along same.

By providing these pumps with a serviceable bottom bearing, as aforesaid, the shaft is steadied against transverse vibration; and though the supplementary bearings still become slightly worn while the pump is being broken in, these bearings are spared the severe wear previously encountered, while the pump is relieved of the destructive rattling which was always detrimental. These beneficial results have removed the uncertain and unsatisfactory features from the operation of vertical multi-stage well pumps 70 and have raised this type of mechanism to a rugged and durable device that has an efficiency and longevity comparing well with pumps of any variety. Though this substantial advance in the art has been basically accomplished by locating a button bearing in the pressureless zone beneath the lowermost impeller, it will be observed also that the particular construction and provisions on said bearing, as hereinbefore described, avoid appreciable interference with the fluid flow, and this interference is totally negligible as compared with the general improvements secured to the pump.

I claim:—

1. In a vertical rotary fluid pump having its inlet passage below, a vertical shaft, an impeller on said shaft, a bearing embracing and supporting the lower extremity of said shaft, an upstanding cap on said bearing 100 and forming a chamber surrounding said shaft, a depending cap within said chamber and having a water tight fit with said shaft, filtering material within said chamber, and a second depending cap above said upstanding cap and having a water tight fit with 105 said shaft.

2. In a rotary deep well water pump having its inlet passage below, the combination with a vertical shaft, of impeller means on said shaft, a pump casing in which said impeller means works, said pump casing having bearing means for said shaft, a separate bearing below said impeller means, the last said bearing being closed around the 110 lower extremity of the shaft and the last said bearing having a filtering chamber surrounding the shaft, and filtering material in said chamber preventing access of sandy or gritty material to the surface of the shaft 115 which runs in the last said bearing.

3. In a rotary deep well water pump having its inlet passage below, the combination with a vertical shaft, of impeller means on said shaft, a pump casing in which said im- 120

steller means works, said pump casing having bearing means for said shaft, and a separate bearing below the impeller means, said bearing being closed around the lower 5 extremity of the shaft, a separate bearing casing attached to the pump casing and supporting the last said bearing, the interior surface of said bearing casing being constructed to substantially conform with the 10 exterior surface of the bearing so that the

velocity change of the water passing through said bearing casing is minimized.

In testimony whereof, I have hereunto set my hand at Los Angeles, California, this twenty-first day of January, 1913.

JOHN A. WINTROATH.

In presence of—
PAUL D. BOWLER,
ROBERT A. STEPS.
